UNITED STATES PATENT OFFICE

103,763

DESIGN FOR A DISPLAY RACK FOR PIECE GOODS

Carl Lang, New York, N. Y.

Application January 25, 1937, Serial No. 67,285

Term of patent 7 years

To all whom it may concern:

Be it known that I, Carl Lang, a citizen of the United States of America, residing in city, county, and State of New York, have invented a new, original, and ornamental Design for a Display Rack for Piece Goods, of which the following is a specification, reference being had to the accompanying drawing, forming part thereof.

Fig. 1 is a top plan view of a display rack for piece goods showing my new design.

Fig. 2 is a front perspective view thereof.

I claim:

The ornamental design for a display rack for piece goods substantially as shown.

CARL LANG.
